FLEXIBLE SHAFT COUPLING

John M. Bowman, Philadelphia, Pa., assignor, by
mesne assignments, to Pennsylvania Patents,
Inc., Carson City, Nev., a corporation of Ne-
vada

Application June 9, 1937, Serial No. 147,324

2 Claims. (Cl. 285—72)

This invention relates to a novel method of terminating a flexible shaft conduit and to a novel terminal structure provided by such method. Although the invention is applicable to flexible shaft conduits used for various purposes, it is particularly directed to those employed in connection with vehicle radio receivers, such as the automobile radio receivers now in general use.

As well known in the art, flexible shafts are used to control the adjustable elements of an automobile radio receiver, such as the tuning and volume control elements, from a point remotely located with respect to the receiving set. The set is usually controlled by means of a control device mounted on the instrument panel of the automobile, and the flexible shafts extend between the said control device and the radio set. The conduit for such a flexible shaft comprises a flexible metal tube formed of spirally-wound strip material, and a loom covering on the said tube. The rotatable flexible shaft extends through the flexible tube. Considerable difficulty has been encountered in the past in providing a suitable terminating structure for such a conduit in order to anchor the ends of the conduit firmly at the radio set and at the control device.

The present invention has for its principal object the provision of a novel method for terminating such a flexible shaft conduit. By means of this method, a terminal is firmly secured to the end of the conduit and the assembled elements are crimped to interlock them together. Moreover, the flexible metal tube forming a part of the conduit is held in firm engagement with the metal terminal so that when the terminal is grounded by virtue of its mechanical attachment to the housing of either the radio set or the control device, the flexible tube is likewise grounded.

The invention may be more clearly understood by reference to the accompanying drawing, in which

Fig. 1 is a perspective view of a cap-like terminal which may be employed according to the invention; and

Figs. 2 to 4 illustrate successive steps in the method of forming the terminal structure.

Referring to Figs. 1 to 4, in accordance with one embodiment of the invention, a terminal in the form of a metallic cap having the shape shown in Figs. 1 and 2 may be employed. This terminal has a head portion 1 with an aperture 2 at the center thereof, and a cylindrical wall 3, the end of which is flared outward as shown at 4. The terminal may be formed from sheet metal in ac-

cordance with any of the known methods of working such material.

The flexible shaft conduit above mentioned is shown in Figs. 2 to 4 and comprises the flexible tube 5 formed of spirally-wound flat metallic strip material and a loom covering 6 over the said tube. As stated above, the flexible control shaft extends through the conduit during use of the same.

In accordance with the present invention, the cap-like material is placed over an end of the conduit as shown in Fig. 2 and the end portion of the conduit, together with the terminal thereon, is placed in a two-part hollow die member 7 having the form shown clearly in Fig. 2. It will be noted that this die member has an annular shoulder 8, a conical surface 9 and another annular shoulder 10. The member is also preferably provided with corrugations 10a to enhance the frictional gripping of the conduit. The initial positioning of the conduit and terminal in die member 7 is as shown in Fig. 2. Following the positioning of the assembled parts in the die member 7, a complementary die member 11 having a pointed end is brought into the position shown in Fig. 2 with its pointed end seated in the opening 2 of the terminal. The member 11 has a cylindrical portion 12 of such diameter that it is adapted to slide snugly within the flexible tube 5. The die member 11 also has an annular shoulder 13 and an arcuate annular surface 14 between the shoulder 13 and the cylindrical portion 15. The latter cylindrical portion is adapted to seat snugly within the complementary end portion 15a of the die member 7.

As the die member 11 is moved toward the right from the position shown in Fig. 2, the conduit and the terminal are held frictionally by the die member 7, and the pointed end enlarges the opening in the terminal and deforms the head of the terminal by pressing it inward. When the surface 14 of die member 11 engages the inner wall of the terminal it exerts longitudinal pressure on the conduit and causes the conduit and the terminal to slide within the die member 7 to the position of Fig. 3. During such movement, the flared end 4 is crimped inward by the surface 9 and finally rests against the shoulder 8, while the opposite flared end of the terminal comes to rest against the shoulder 10, as shown in Fig. 3. The conduit and terminal are then held firmly by the die member 7 while the die member 11 exerts further longitudinal pressure. The surface 9 of die member 7 presses the outer part of the terminal against the loom 6, while the shoulder 13 of die member 11 crimps the tube 5, as shown at 16, and

the surface 14 presses the inner part of the terminal firmly against the inner surface of tube 5. The end portions of the tube 5 and the loom 6 are flared and compressed between the inner and outer parts of the terminal.

When the die member 11 is removed, the resiliency of the tube 5 causes the deformed end thereof to take the form shown in Fig. 4. The parts are thus firmly attached to one another and are interlocked with respect to one another and, at the same time, the metal terminal is in snug engagement with the end of the deformed end of tube 5. The flexible shaft conduit thus terminated may be attached to the metallic radio set 15 housing or to the metallic housing of the control device above mentioned in any suitable manner, for example by means of a collar adapted to engage the flared end or flange of the terminal and which may be secured to either one of the housings. This, the end of the flexible shaft conduit 20 may be firmly anchored and, at the same time, the metallic tube 5 may be efficiently grounded.

It will be understood that various other embodiments of the invention are possible. The invention contemplates broadly the die-forming of a terminal and an associated end of a flexible shaft conduit, so as to press the elements into firm engagement and to crimp them to interlock them together. It will be apparent, therefore, 30 that the invention is not limited to the specific forms herein illustrated and described.

I claim:

1. A terminal structure for a flexible conduit including a flexible metal tube and a loom covering thereon, said structure comprising a stamped metal terminal member fitted onto an end of said

conduit, said member having inner and outer concentric parts connected together by an annular connecting portion extending about and covering the edge of the conduit end, the said metal tube being expanded at its end to form an internal 5 annular recess of substantial area, the inner part of said member being seated in said recess, the outer part of said member embracing said loom covering over a substantial end area thereof and being deformed or crimped inwardly to tightly 10 engage the loom covering, and the end of the composite structure being flared outwardly, whereby said terminal member and said conduit are interlocked with one another against longitudinal relative movement. 15

2. A terminal structure for a flexible conduit including a flexible resilient metal tube and a covering thereon, said structure comprising a stamped metal terminal member fitted onto an end of said conduit, said member having inner 20 and outer concentric parts connected together by an annular connecting portion extending about and covering the edge of the conduit end, the inner part of said member engaging the inner wall of said tube at the end thereof, the outer part of 25 said member embracing said covering over a substantial end area thereof and being deformed or crimped inwardly to tightly engage the covering, and the end of the composite structure being flared outwardly, the diameter of the flared end 30 being greater than the diameter of the inwardly crimped portion of said outer part, whereby said terminal member and said conduit are interlocked with one another against longitudinal relative movement. 35

JOHN M. BOWMAN.
